UNITED STATES PATENT OFFICE.

GEORGE A. CUMMINGS, OF SPOKANE, WASHINGTON, ASSIGNOR OF ONE-HALF TO
CHARLES H. CUMMINGS, OF SPOKANE, WASHINGTON.

DIRECTION INDICATOR.

Application filed June 19, 1922. Serial No. 569,203.

To all whom it may concern:

Be it known that I, GEORGE A. CUMMINGS, a citizen of the United States, residing at Spokane, in the county of Spokane and 5 State of Washington, have invented new and useful Improvements in Direction Indicators, of which the following is a specification.

This invention relates to improvements in 10 direction indicators for automobiles of that class comprising a plurality of operatively connected members adapted to be projected into an indicating or retracted into a non-indicating position.

15 It is a special feature of this invention to provide an indicator of this character in which one of the members is in the form of an enclosing casing into and out of which the remaining member may be moved. In 20 other words, the members of my improved device are movable, one within the plane of the other.

A further feature consists in equipping 25 the casing member with a direction mirror which is at all times available in its utility as a mirror because of my improved feature of moving one indicating member into the other.

By reason of the fact that one of the 30 indicating members is a casing, I am able to not only protect the remaining member from the effects of the elements, but I also protect the movable parts constituting the operative connections between said members.

35 The invention has many other features of novelty which will be more fully described in connection with the accompanying drawing and which will be more particularly pointed out in and by the appended 40 claims.

In the drawing:

Fig. 1 is a view looking from the rear of 45 an auto and on the left hand side thereof, and showing the device of my invention in laterally projecting relation to the wind-shield.

Fig. 2 is a view looking from the front of the auto.

Fig. 3 is a view looking in the direction 50 of Fig. 1, with the device adjusted to indicate that the driver intends to turn to the right.

Fig. 4, is a similar view showing the device 55 adjusted to indicate that the driver intends to turn to the left.

Fig. 5, is an enlarged sectional view on line 5—5 of Fig. 4.

Figure 6, is an enlarged sectional view on line 6—6 of Fig. 2.

Fig. 7, is a sectional view on line 7—7 of Fig. 6.

Like characters of reference designate similar parts throughout the different figures of the drawing.

I have briefly indicated the left hand 65 wind-shield post at 1, the frame having two members designated at 2 and 3. The member 2, of the frame, is preferably tubular and on the outer end thereof is rigidly mounted a block 4, having journalling hubs 5 and 6 70 and a supporting hub 7. The end 8, of member 2, is shown threaded into hub 5. Inside of member 2, is a tubular operating shaft 9, on the inner end of which is fixed an operating lever 10. The shaft 9, extends 75 through hub 6, and carries on its outer end a bevel gear 11, which is fixed thereto, as by a pin 12. A stationary chain wheel 13, has a stud shaft 14, which is fixedly mounted in the supporting hub 7, whereby said wheel 80 will be securely fixed against rotation. Rotatively mounted on the periphery of hub 7, is a bevel gear 15, which meshes with gear 11 and from which latter it is operated.

My invention includes a member which I 85 have shown in the form of a casing which I will generally designate at 16. This casing has front and rear walls 17 and 18, respectively. On the rear wall 18, is a mirror 19. The rear wall is keyed or otherwise 90 non-rotatively mounted on gear 15, as shown at 20, so that as gear 15, is turned in opposite directions, it will tilt the casing 16. The normal or non-indicating position is 95 shown in Fig. 1, and the indicating positions in Figs. 3 and 4. Now it will be seen that the casing is elongated in form and that it is pivoted or mounted to swing on or with gear 15, about a fixed axis which is nearer the top than the bottom of said casing. In fact, I prefer to dispose this axis at a high point for two reasons, namely; to obtain automatic return by gravity, and to increase the extent of projection when the device is in an indicating adjustment, as 100 will be presently described with more particularity.

The wall 17, has a flat and shallow cavity 21, for receiving certain chain wheels, a flange 22, serving as stock for connecting 110

screws 23. The lower ends of the walls 17 and 18, are connected by a bolt 24, having reduced ends 25 onto which nuts 26, are threaded to hold the walls in place. This bolt forms a journal for a lower or minor chain wheel rotatively mounted. To this minor wheel is fixed by rivets 28, or like means, an indicator 29, on the outer end of which a hand is formed. Thus, I will term the wheel 27, the indicator wheel. A chain or cable 30, is trained about wheels 13 and 27, and said chain is shown secured to said wheels at 31 and 32, diagrammatically. By securing the chain 30, to said wheels, I therefore by limit movement of the parts into predetermined extreme positions, the points of anchorage of the chain being determined with that end in view.

However, in one position, namely the retracted position, the shoulder 33, may act as an abutment for the indicator 29. The wall 18, may be secured to wall 17, by screws 23, as previously referred to, the walls being open at their outer edge to permit the indicator 29 to swing into and out of the casing 16.

I will next describe the operation of my improved device.

Assuming that the parts are in a non-indicating position shown in Fig. 1, and that the driver intends to signal or indicate to a following vehicle that he will turn to the right, he will shift the lever 10, turning wheel 11. This will turn wheel 15 and shift the casing to the position shown in Figure 3. By reason of the fact that chain wheel 13, does not partake of this shifting movement of the casing 16, the chain or cable 30, will impart enough rotary adjustment to wheel 27, to shift the indicator 29, into the position shown in Figure 3. If the driver wishes to signal that he is about to turn to the left, he will impart a further adjustment to lever 10, than that shown in Fig. 3, and as indicated in Fig. 4. Thus, the indicator 29, and the casing 16, are projected into alined relation.

Looking at either Figs. 3 or 4, it will be seen that the greater mass of the device is at the left of a vertical line intersecting the center of wheel 13, hence, the device will always seek the pendent position shown in Fig. 1. This is due to the fact that the axis of swing of the device is very near the top of casing 16.

It will be seen that my device consists of a plurality of jointed indicating members, one member being hollow and the other member being solid (in the sense that it is not hollow) and that said members are movable in the same plane as the solid member moves into and out of said hollow member.

By having one, and only one member hollow, and the other member solid, I not only

save the cost of making both hollow, which is considerable, but I am able to enclose the solid member and its pivotal mounting from the effects of the elements.

It will also be seen that the solid member 29, because of the fact that it moves into and out of member 18, can never intercept the view from the mirror 19, which would not be true if the member 29 swung past the hollow member in a parallel plane. Thus, in any adjustment, the driver has full advantage of an uninterrupted vision to and from the mirror.

It is believed that my invention will be clear from the foregoing description and I do not wish to be limited thereto except for such limitations as the claims may import.

I claim:—

1. A direction indicator mechanism for attachment to an automobile, comprising a frame having a block provided with supporting and journalling sleeves in intersecting and right angular relation to each other, an indicator casing having a slot in one side thereof, a major chain wheel in said casing and having a stud fixed in said supporting sleeve, a casing bevel gear rotatively mounted on the periphery of said supporting sleeve and fixed to and supporting said casing, an operating shaft rotatable in said journalling sleeve and having a bevel gear meshing with said casing gear, a minor chain wheel journalled in said casing, an indicator mounted on said minor wheel and adapted to be moved through said slot into and out of said casing, and a chain trained about said major and minor wheels.

2. A direction indicator mechanism for an automobile, comprising a frame having a block provided with journalling and supporting hubs, a casing having a bevel gear fixed thereto and said gear being rotatively mounted on the periphery of said supporting hub, a stationary major chain wheel having a stud shaft fixed in said supporting hub and said wheel being disposed in said casing, a minor chain wheel rotatively journalled in said casing, a chain trained about said chain wheels, an indicator fixed to said minor chain wheel, an actuating bevel gear meshing with said casing gear, and a shaft rotatable in said journalling hub for rotating said actuating gear to swing said casing and indicator into alined projecting relation or returning said casing to a vertical position and retracting said indicator into said casing.

3. A direction indicator mechanism for attachment to a motor vehicle, comprising a frame, a casing rotatable on said frame and having a slot therein, a stationary chain wheel in said casing, an indicator chain wheel rotatably mounted in said casing, a chain trained about said wheels, an indicator fixed to said indicator wheel movable

through said slot, whereby when said casing is swung into an indicating position said indicator will be projected out of said casing or when said casing is returned to a 5 non-indicating position said indicator will be retracted into said casing.

4. A direction indicator mechanism for attachment to a motor vehicle, comprising in combination, a support, an indicator casing 10 pivoted on said support to be swung into and out of an indicating position and hav-

ing a direction mirror on its rear face, an indicator pivotally mounted in said casing, and means causing said indicator to swing out of and into said casing as the latter 15 moves into and out of indicating positions, whereby said indicator will be out of intersecting range of said mirror.

In testimony that I claim the foregoing as my own, I hereby affix my signature. 20

GEORGE A. CUMMINGS.
